HENRY HARDISTY, OF RAYMOND, WASHINGTON, ASSIGNOR OF ONE-HALF TO ELIAS PIERSON, OF SOUTH BEND, WASHINGTON.

LOGGING-HOOK.

1,139,761.

Specification of Letters Patent. Patented May 18, 1915.

Application filed May 4, 1914. Serial No. 836,250.

To all whom it may concern:

Be it known that I, HENRY HARDISTY, a citizen of the United States, residing at Raymond, in the county of Pacific and 5 State of Washington, have invented a new and useful Logging-Hook, of which the following is a specification.

The invention relates to improvements in logging hooks.

10 The object of the present invention is to improve the construction of logging hooks and to provide a simple, inexpensive and efficient logging hook of light strong and durable construction adapted to save time 15 and labor in various logging operations and equipped with means for effectually preventing it from coming accidentally unhooked.

With these and other objects in view the 20 invention consists in the construction and novel combination of parts hereinafter fully described and illustrated in the accompanying drawing and pointed out in the claims hereto appended, it being understood that 25 various changes in the form, proportion and size and minor details of construction within the scope of the claims may be resorted to without departing from the spirit or sacrificing any of the advantages of the invention. 30

In the drawing—Figure 1 is a perspective view of a logging hook constructed in accordance with this invention and shown locked. Fig. 2 is a longitudinal sectional view of the same. Fig. 3 is a transverse sectional view on the line 3—3 of Fig. 2. Fig. 4 is a perspective view of the logging hook, the same being open.

Like numerals of reference designate 40 corresponding parts in all the figures of the drawing.

In the accompanying drawing in which is illustrated the preferred embodiment of the invention 1 designates the body portion 45 of a logging hook consisting substantially of a link provided with one side at a point intermediate its ends with an opening 2 forming inner and outer substantially hooked-shaped terminal portions 3 and 4.

50 The inner hooked-shaped terminal portion of the body 1 is provided with an eye or opening 5 and is designed to receive a link of a log or other chain (not shown) and the said inner hooked-shaped portion 3 has its 55 end 6 bifurcated for the reception of a re-

duced terminal portion 7 of a latch or lap member 8. The reduced end 7 of the latch member is pivoted in the slot or bifurcation of the end 6 by a transverse rivet 9 or other suitable fastening device and the said latch member which constitutes a latch section is adapted to extend across the opening 2 of the body portion 1 to complete that side of the hook for confining a link or similar member in the closed opening of the logging hook. The latch member is adapted to be swung upwardly or outwardly from the closed position shown in Fig. 1 of the drawing to the position shown in Fig. 4 to open the logging hook and enable the outer terminal hooked-shaped portion 4 to be engaged with or disengaged from a link. The outer terminal hooked-shaped portion 4 is adapted to be readily engaged with a link of a chain when the latch member is in its 75 open position.

The outer terminal hooked-shaped portion is provided at the outer side of the opening 2 with a longitudinal extension 10 reduced at the outer side to form a recess 80 11 for the reception of the overlapping portion 12 of the latch member, and the latter is reduced at the inner side at 13 to receive the reduced extension 10 of the outer hooked-shaped portion of the body. The 85 extension 10 and the reduced portion 12 of the pivoted latch member have flat faces at their recesses to fit against each other and the said parts are provided with terminal lugs 14 and 15 which fit in corresponding 90 slots or openings 16 and 17. When the latch member is closed it is interlocked with the extension 10 against lateral and longitudinal movement. The overlapped reduced portions of the body of the logging hook 95 and the latch member have a combined diameter substantially equal to the diameter of the metal of the outer terminal hooked-shaped portion 4, and they are substantially semi-circular in cross-section and are adapted to receive a sleeve 18 which embraces the 100 said reduced portions and retains the same in their interlocked relation whereby the latch member is secured in its closed position and the logging hook effectually prevented from becoming accidentally disconnected or unhooked from a logging chain.

The locking sleeve is capable of rotary movement on the reduced overlapped portions 10 and 12 to carry the interior groove 110

19 into and out of alignment with a longitudinal rib or key 20 formed integrally with the latch member and located at the outer side thereof as clearly illustrated in Fig. 1 5 of the drawing. When the groove of the locking sleeve is arranged in alignment with the guide rib or key the sleeve is adapted to slide inwardly or rearwardly to a point beyond the reduced extension 10. The portion 10 of the locking member from which the rib or key 20 projects is round to conform to the configuration of the interior of the sleeve. This will release the latch member and permit the same to be swung to its open 15 position. When the latch member is closed and it is desired to lock the same in such position the sleeve is moved outwardly along the latch member to a point beyond the guiding rib or key 20 and is then rotated to 20 carry the groove out of alignment with the said rib or key 20. The outer terminal hooked-shaped portion is provided adjacent to the reduced extension 10 with a projecting flange 21 arranged in spaced relation 25 with a guiding rib or key 20 and co-operating with the same to hold the sleeve against longitudinal movement in either direction when the groove is turned away from the rib or key 20.

30 The logging hook is simple in its operation and may be quickly engaged with and disengaged from a chain and as the reduced portion of the latch is supported by the extension 10 and the said parts are embraced by the locking ring, the logging hook may be made considerably lighter than the common form hook customarily employed in such logging operations as the point of such ordinary hook is unsupported and necessarily requires a heavier construction than the device of the present invention. While the hook of the present invention is designed primarily for logging purposes it may be advantageously employed wherever a device 40 of this character is desirable.

45 What is claimed is:—

1. A hook of the class described comprising a body having an opening at one side and provided at one of its terminals with a reduced extension having a flat outer face, a latch member pivoted at the other terminal and extending across the said opening and provided with a reduced portion having a flat inner face, the flat faces of the two 50 reduced parts being in contact when they are overlapped, said latch member being provided adjacent to its pivoted end with a longitudinal rib extending from the pivoted end of the latch member to the reduced por-

tion, and a sleeve arranged on the latch 60 member and provided with a groove adapted to receive the said rib, whereby the sleeve is slideable along the latch member and is movable to and from the said reduced portions, said sleeve when arranged on the overlapped reduced parts being located beyond the rib, whereby the sleeve is adapted to be rotated to carry the groove thereof away from the rib and thereby retain the sleeve on the said reduced parts for holding the 70 latch member in its closed position.

2. A hook of the class described comprising a body provided at one side with an opening and having a reduced extension at one side of the opening, said extension being provided at one end with an outwardly projecting lug and having a transverse slot at its inner end, a latch member pivoted at the other side of the opening and having a reduced portion overlapping the said reduced extension, and provided at its inner end with a transverse slot and having an inwardly projecting lug at its outer end, the slots of the said overlapped portion and extension receiving the lugs thereof and interlocking the said parts at each end of the same, and a sleeve slideable on the latch member and movable to and from the overlapped portion and extension and adapted to retain the latter in their interlocked relation.

3. A hook of the class described comprising a body having an opening at one side, and provided at one of its terminals with a reduced extension, a latch member pivoted 95 at the other terminal and extending across the said opening and provided with a reduced portion which is caused to overlap the said reduced extension, the combined diameter of the reduced portion and extension 100 being substantially equal to the diameter of the adjacent portion of the body from which the said extension projects, interfitting lugs and slots provided in the reduced extension and reduced portion to provide an interlocking of the parts, a longitudinal rib provided on the latch member, a sleeve having a groove to receive the rib, and a stop provided on the body adjacent to the reduced extension and spaced from the rib.

110 In testimony, that I claim the foregoing as my own, I have hereto affixed my signature in the presence of two witnesses.

HENRY HARDISTY.
